UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed November 18, 1922. Serial No. 601,829.

To all whom it may concern:

Be it known that I, FRED S. CARR, a citizen of the United States, and a resident of Newton, in the county of Middlesex and State of Massachusetts, have invented an Improvement in Fasteners, of which the following description, in connection with the accompanying drawings, is a specification, like characters on the drawings representing like parts.

This invention pertains to improvements in fasteners, and more particularly, though not exclusively, to that type of fastener commonly used for securing carpets, rugs or the like to floors.

In the drawings, which show a preferred form of one embodiment of my invention:

Figure 1 is a plan view of a portion of a rug or carpet showing in dotted lines the position of an underlying fastener;

Fig. 2 is a diagrammatic view showing the warp and weft threads to which the fastener socket is attached and the socket prongs penetrating these warp and weft threads and clenched thereover;

Fig. 3 is a section on the line 3—3 of Fig. 1, being partly in elevation and showing the preferred form of stud and socket secured respectively to the floor and to the rug or carpet thereon;

Fig. 4 is a section on the line 4—4 of Fig. 3, illustrating how the pile of the rug or carpet may overlie and conceal the socket securing prongs; and

Fig. 5 is a plan view of the socket before attachment thereof to the rug or carpet.

Referring to the drawings and to the preferred form of my invention selected for illustrative purposes, I have shown a stud including a screw portion 6 and a head portion 7. The screw portion of the stud may be entered in the floor 8 of the room or automobile in which the rug or carpet is to be used. The cooperating socket may include a plate 9 peripherally curved upwardly and presenting a plurality of warp and weft penetrating prongs 10 arising therefrom. The socket casing may also include a spring-securing plate or disc 11 adapted to overlie and hold in place a spring 12, preferably annular as indicated, and adapted to engage the neck of the stud beneath the head 7 thereof.

The plate 9 is apertured to admit the head of the stud, and the spring-securing

plate or disc 11 is also preferably apertured to permit passage of the head 7 of the stud into the plane of the top of the spring-securing plate or disc 11 which may be secured to the plate 9 by striking up and bending over the lower edge thereof portions 13, as best shown in Fig. 5. Where the spring-securing plate or disc 11 is curved in cross-section as shown, an annular depression 15 is provided between the spring-securing plate or disc 11 and the peripheral portion of the socket. When the prongs 10 have penetrated the warp and weft threads 14 of the rug or carpet, these prongs may be bent inwardly and draw downwardly any warp or weft threads lying thereunder into the annular depression 15, so that the upper surface of the carpet will show very little elevation at the point underlain by the fastener and, further, so that the prongs 10 will be particularly effectively concealed by the pile of the rug or carpet, as best shown in Fig. 4.

Where, as in the preferred form of my invention illustrated, the socket is relatively thin and wide and the stud presents a relatively wide and thin head which when entered in the socket does not lie substantially above the plane of the upper face thereof, not only is the formation of humps or bunches in the carpet minimized, but the tendency to excessive wear of the carpet immediately above the fastener is to a considerable degree reduced.

While I have shown and described a preferred form of my invention, it will be understood that my invention is not limited thereto but is best defined in the following claims.

Claims:

1. A fastener socket for application to a carpet or the like comprising, in combination, a socket including a lower member presenting an aperture to receive the head of a stud, resilient means partially intersecting said aperture releasably to grip a stud entered therein, and a spring-holding member secured to said lower member, said lower member and spring-holding member together constituting a casing, the outer edge of said lower member having upwardly extending prongs adapted to be bent downwardly and inwardly to engage over the warp of the carpet while concealed from view by the pile of the carpet.

2. A fastener socket for application to a carpet or the like comprising, in combination, a socket including a lower member presenting an aperture to receive the head 5 of a stud, resilient means partially intersecting said aperture releasably to grip a stud entered therein, and a spring-holding member secured to said lower member, said lower member and spring-holding member 10 together constituting a casing, the outer edge of said lower member having upwardly extending prongs adapted to be bent

downwardly and inwardly to engage over the warp of the carpet while concealed from view by the pile of the carpet, said lower member flaring upwardly adjacent its periphery to provide a groove between its rim and said spring-holding member into which said prongs may press the engaged warp and weft of the carpet. 15

In testimony whereof, I have signed my name to this specification. 20

FRED S. CARR.
